UNITED STATES PATENT OFFICE.

JAMES V. BRADY, OF SONORA, ILLINOIS.

CULTIVATOR.

SPECIFICATION forming part of Letters Patent No. 530,879, dated December 11, 1894.

Application filed April 13, 1894. Serial No. 507,422. (No model.)

To all whom it may concern:

Be it known that I, JAMES V. BRADY, a citizen of the United States, residing at Sonora, in the county of Hancock and State of Illinois, 5 have invented certain new and useful Improvements in Cultivators; and I do hereby declare the following to be a full, clear, and exact description of the invention, such as will enable others skilled in the art to which it appertains to make and use the same.

This invention relates to cultivators.

The object is to produce a cultivator, in which the teeth or shovels may be adjusted independently of the drag-bars, in groups or 15 pairs, to regulate the depth to which the teeth enter the ground; and further, in which each tooth may be separately adjusted to adapt the cultivator to the width of the rows of the crop.

With this and other objects in view, the invention consists in the combination of parts hereinafter described and claimed.

The invention is illustrated in the accompanying drawings, in which—

Figure 1—is a view in perspective, showing the drag-bars of a cultivator, the cross-beams adjustable thereon and provided with stirrup-clamps, and the toothed shanks separately and adjustably held by the clamps. Fig. 2—

30 is a view in side elevation, showing a cross-beam adjustably held on the drag-bar and the toothed shanks clamped to the beam, also, the relative lengths and arrangement of the shanks. Fig. 3—is a view in front elevation

35 of one of the slotted cross-beams, showing the stirrup-clamps adjustably seated in the slots, and a set-screw or bolt passing through an enlargement of the beam to a vertical, central opening and binding against the drag-bar

40 therein. Fig. 4—is a top plan view of the same, showing the slots in the beams and the threaded extremities of the U-shaped clamps projecting through the slots and provided with lock-nuts. Fig. 5—is a fragmentary view

45 showing a modified form, in which the central enlargement of the beam is chambered to receive the curved end of the drag-bar which is slotted laterally and held by binding

50 screws or bolts passing laterally through the enlargement and the slots, above and below the other part of the beam, the construction

and arrangement permitting slight play of the beam.

In the drawings, A, represents the drag-bars of a cultivator, the rear ends, a, a, of 55 which are flattened and curved downward.

B, represents slotted cross-beams which are respectively provided about midway of their length with an enlargement, b, projecting vertically from opposite sides of the beam, at a 60 right angle thereto. This enlargement is vertically and centrally bored at b², to receive the curved extremity of the drag-bar to which the beam is adjustably connected by a binding screw, bolt, or other device, b³.

C represents stirrups, yokes, or U-shaped clamps, which are adjustably seated in perforations or the slots, b⁴, toward the outer ends of the beams, with their curved portion 65 projecting through the slots and below the lower face of the beams, and their extremities 70 threaded to receive lock-nuts, c, c.

D, represents curved toothed shanks, here shown arranged in pairs or two on each beam. These shanks are separately secured to the 75 under side of the beam, by being passed through the depending stirrups, and are adjustably held by the lock-nuts, c, c, either rigidly or yieldingly, as desired. One shank of a pair is given an increased length by which 80 the shanks may be relatively adjusted to work in a follow-up series, as shown in Fig. 1 of the drawings, or parallel, in pairs, or fours, according to the number employed.

Where the soil is hard or stony, it may be 85 found necessary to give the cross-beams slight play, and avoid shocks or strains on the teeth. To effect this, the construction illustrated in Fig. 5 is employed, and consists in chambering the central enlargement of the beams or 90 making it U-shaped, to receive the flattened extremities of the drag-bars, which are of a width sufficient readily to admit of slots being formed therein, without materially weakening them, and through these slots, screws, 95 bolts, or pins from the enlargement are passed and work loosely therein.

Among the numerous and important advantages of this invention may be mentioned, the ease and convenience with which an entire re-arrangement of the teeth, shovels, or points, may be effected, to adapt the cultivator 100

to perform work of various kinds efficiently; also the connection between the cross-beams and the shanks, by which the latter may be separately and accurately adjusted and rigidly or yieldingly secured.

Having thus described my invention, what I claim as new, and desire to secure by Letters Patent, is—

1. The combination with a drag-bar, having its rear end curved downward, of a cross-beam provided about midway of its length with an enlargement having a central vertical perforation or chamber and binding screws or bolts to retain the drag-bar in desired position, and provided, further, with slots toward its ends, and of stirrups or yokes set in the slots with their curved portion downward and having their extremities threaded and provided with nuts, all substantially as and for the purpose described.
2. The combination with drag-bars, having

their rear ends curved downward, of cross-beams provided about midway of their length with enlargements having central vertical perforations or chambers and binding screws or bolts to retain the drag-bars in desired position, and provided, further, with slots toward its ends, of stirrups or yokes set in the slots with their curved portion downward and having their extremities threaded and provided with nuts, and teeth having shanks adjustably held by the yokes, one shank of a pair being of greater length than the other, all substantially as and for the purpose set forth.

In testimony whereof I affix my signature in presence of two witnesses.

JAMES V. BRADY.
